[57] CLAIM

The ornamental design for a front portion of a connector, as shown and described.

DESCRIPTION

FIG. 1 is a perspective view of a first embodiment of a front portion of a connector showing my new design;

FIG. 2 is a top plan view thereof;

FIG. 3 is a left side elevational view thereof;

FIG. 4 is a front elevational view thereof;

FIG. 5 is a bottom plan view thereof; and

FIG. 6 is a right side elevational view thereof. The body portions shown in broken line are for the purpose of illustrating environmental structure only and form no part of the design of claimed in the first embodiment; and,

FIG. 7 is a perspective view of a second embodiment of a front portion of a connector showing my new design. The front elevational view of the embodiment of FIG. 7 is shown in FIG. 4.

The body portions shown in broken line are for the purpose of illustrating environmental structure only and form no part of the design of claimed in the second embodiment.
